Primary Examiner — Eliza Z Harvey*Assistant Examiner* — Landon Thomas Cassell(74) Attorney, Agent, or Firm — LEGALFORCE RAPC
WORLDWIDE(57) CLAIM

The ornamental design for a neck massage device, as shown and described.

DESCRIPTION

FIG. 1 is a front top right side perspective view for a neck massage device, showing my new design;

FIG. 2 is a bottom right side perspective view thereof;

FIG. 3 is a front elevational view thereof;

FIG. 4 is a rear elevational view thereof;

FIG. 5 is a left side elevational view thereof, the right side elevational view being a mirror image;

FIG. 6 is a top plan view thereof; and,

FIG. 7 is a bottom plan view thereof.

The broken lines in the drawings depict portions of the neck massage device that form no part of the claimed design.
